(57) **CLAIM**

The ornamental design for a container holder, as shown and described.

DESCRIPTION

FIG. 1 is a top perspective view of a container holder, showing my new design;

FIG. 2 is a top perspective view thereof;

FIG. 3 is a bottom perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.

The broken lines showing an ironing board in FIG. 1 depict environmental matter and form no part of the claimed design. The broken lines in FIGS. 8 and 9 depict portions of the container holder that form no part of the claimed design.

1 Claim, 9 Drawing Sheets
